UNITED STATES PATENT OFFICE.

HORACE RESLEY, OF CUMBERLAND, MARYLAND.

IMPROVEMENT IN EXPLOSIVE SHELLS FOR ORDNANCE.

Specification forming part of Letters Patent No. 37,520, dated January 27, 1863.

To all whom it may concern:

Be it known that I, HORACE RESLEY, of Cumberland, in the State of Maryland, have invented a certain new and useful Improvement on Shells for Ordnance; and I do hereby declare that the following is a full, clear, and exact description thereof, reference being had to the accompanying drawings, and to the letters and marks thereon.

Commonly, in shells where the percussion-cap or like means is used to ignite the explosive material within the shell it is placed at the forward end of the shell, and so arranged as to be operated when the shell strikes against the object to which it is directed. An important objection to this position of the cap is that the explosion of the shell will occur before the shell fully enters the object, and thus much of its value as a destructive agent is lost. In order to make available the full power of the shell, it has been proposed to place the means for producing the ignition of the explosive material in recesses in the sides or periphery of the shell, so that the explosion will not take place until the greater part of the shell is within the object.

My invention relates to this class of shells; and it consists in so arranging the discharging mechanism with an adjustable plate as to prevent accidental discharge, and to provide for the explosion when desired. These means, as shown by the drawings forming part of this specification, are placed near the base of the shell and between the expanding bands thereof; but, as is evident, they may be placed at such other point of the periphery as may be deemed preferable, the better to adapt them to the particular shell to which they may be applied. Any such number of these means may be used on any one shell that may be regarded as requisite.

Figure 1 of the drawings hereof represents a shell in view by elevation, having my improvement attached thereto, with the guard-plate so arranged that the hammer will not operate. Fig. 2 is a like view with the guard-plate removed. Fig. 3 is a view of a section of a shell with the means attached, the guard-plate being so arranged as to allow the hammer to be operated. Fig. 4 is a view

of the bottom of the shell, and Fig. 5 is a view of the upper part of the hammer.

In each of these figures where like parts are shown like marks and figures are used to designate the parts.

The nipple, on which may be placed a percussion-cap or the copper cartridge, is marked *a*, and is placed in a recess in the side of the shell. Above the nipple is the hammer, composed of two pieces, *b* and *c*, a pin, *d*, of the one piece fitting into a hole, *e*, of the other piece, and thus being a pivot for the turning of the piece *c*. Both of these pieces may be made so as to be but one piece, in which case a pin will be attached to the upper part of *c* and fit into a hole in the recess above it, so that it may be turned, and the lower part, *b*, will then be round instead of square, as here shown. A spring, of metal or india-rubber, *f*, is attached to the part *c*, the tendency of which is to force this part out from the periphery of the shell, and thus put it in the proper position to be operated when it comes in contact with an opposing object. As shown by the drawings, this spring is made of india-rubber, the outer end of it being clamped by the guard-plate. If made of metal, the outer end can be affixed in the recess of the shell.

The part *b* of the hammer has a shoulder, *h*, against which the edge of the guard-plate bears when this plate is so held as not to allow the hammer to hit the cap. A screw or pin, *i*, holds the guard-plate *o* in this position to check the operation of the hammer, and recesses *j* in the edge of the guard-plate permit the sliding of it up or down to adapt it to the two positions of allowing the hammer to be operated or to prevent its being operated.

When the shell is not to be used, the upper part of the hammer will be out, as it will be at all times except when in the gun or mortar, and the guard-plate *o* will be held up by the screw *i*, as is shown by Fig. 1. When the shell is to be used, the screw *i* will be removed and the guard-plate *o* allowed to play, as is shown by Fig. 3.

In preparing the shell to be placed in the gun or mortar, the screw *i* is taken out and that part *c* of the hammer pressed into the recess, the shell then being forced into the gun. On

coming out of the gun in discharge this part *c* of the hammer is thrown out by its spring and ready to be acted upon, as is shown by Fig. 4.

What I claim as my invention, and desire to secure by Letters Patent, is—

The arrangement of the means or devices herein set forth for protecting the operating

mechanism and providing for the discharge when desired.

This specification signed this 9th day of September, 1862.

H. RESLEY.
